UNITED STATES PATENT OFFICE.

HENRY J. MARK, OF ST. LOUIS, MISSOURI.

VENEER-CUTTING KNIFE.

SPECIFICATION forming part of Letters Patent No. 507,713, dated October 31, 1893.

Application filed October 27, 1892. Serial No. 450,094. (No model.)

To all whom it may concern:

Be it known that I, HENRY J. MARK, of St. Louis, Missouri, have made a new and useful Improvement in Veneer-Cutting Knives, of 5 which the following is a full, clear, and exact description.

The improvement relates more especially to the cutting edge of the knife, which consists substantially as is hereinafter set forth 10 and claimed, aided by the annexed drawings, making part of this specification, in which—

Figure 1 is a side elevation of the improved knife, looking toward that side thereof which is presented to the block from which the veneers are cut; Fig. 2 an elevation of the opposite side of the knife; Fig. 3 a longitudinal section on the line 3—3 of Fig. 1; Fig. 4 a longitudinal section on the line 4—4 of Fig. 1; and Fig. 5 a cross section on the line 5—5 20 of Fig. 1.

The same letters of reference denote the same parts.

The knife A is of suitable material, and of proper size and dimensions, substantially as 25 shown, for veneer-cutting work. That side, B, of the knife which is presented to the piece of wood from which the veneers are cut is fluted, the flutings b extending longitudinally in the knife, and to the cutting edge thereof, 30 substantially as shown. The opposite side, C, of the knife is flat. The cutting edge, D, is beveled, the bevel being formed upon the reverse side, d, of the cutting-edge, as shown. The cutting edge of the knife is thus in the 35 form of a serration, or rather a series of beveled points d', each of which is adapted to make a shearing cut. At the same time, by

reason of its oblique direction shown, the edge D, as a whole, is adapted to cut in a shearing manner. In addition to this advantage the improved knife can be readily sharpened by turning its beveled side to the sharpening tool. The knife at its side edges, a, a', is suitably shaped substantially as shown to adapt it to be held in the usual knife-holder, not shown. The cutting edge being oblique, performs two functions, viz., the ordinary function of giving the terminal or outer edge a shearing effect, and the additional function of giving the depressions between the teeth the same or similar effect. In addition, the intervals between the series of teeth allow each tooth to take hold of the material to be cut successively, thus giving each tooth a shearing effect of its own and at the same time necessitating less driving power to accomplish the result than would be the case of a fluted knife without an oblique edge or a knife with an oblique edge and not serrated. 40 45 50 55 60

I claim—

A veneer cutting knife consisting of a flat and a fluted side, an oblique serrated cutting edge, a beveled sharpening surface formed on the flat side and co-operating with the fluted side, whereby a series of individually shearing cutting teeth is formed, substantially as set forth. 65

Witness my hand this 24th day of October, 1892.

HENRY J. MARK.
